SHEET MATERIAL STACKER

Nevell R. Jones, deceased, late of Haddonfield, N. J., by Mina R. Jones, executrix, Redwood, N. Y., and Benjamin R. Carson, assignors to Radio Corporation of America, a corporation of Delaware

Original application March 26, 1937, Serial No. 133,137. Divided and this application April 30, 1938, Serial No. 205,382

5 Claims. (CL. 271—87)

This invention relates to stacking apparatus for sheet material, and more particularly to stacking apparatus as applied to photoradio or facsimile machines and, furthermore, comprises a 5 division of co-pending application Serial Number 133,137 filed March 26, 1937.

Such machines are well known at the present time in their broader concepts, and this apparatus has been particularly useful for use with 10 the so-called Young facsimile receiver as illustrated in U. S. Patent Re. 20,152, granted to C. J. Young. The Young machine in its broadest concept comprises a receiver drum with a helical section mounted on the periphery thereof, the 15 drum rotating in synchronism with a transmitter drum. The transmitter picks up line by line electrical impulses representative of the optical density value along each line, and these impulses are transmitted to the receiver where they 20 actuate a striker or presser mechanism which is located immediately adjacent the elongated spiral or helix on the receiver drum. The recording material has in general been paper although, of course, other recording mediums may be used. 25 A sheet of carbon paper is maintained in intimate relationship with the recording material along a line tangential to the receiver drum and these two materials pass together between the receiver drum and the striker or presser bar or 30 bars so that impulses which actuate the bar or bars leave a deposit of elemental size on the recording material at the point where the striker or presser bar or bars is forced against the raised helix. As this application is not concerned particularly with the operating details of this portion of the machine, for a more complete understanding, reference should be had to the Young 35 Patent Re. 20,152, hereinbefore referred to.

It is within the contemplation of present day 40 facsimile practice that a portion of the expense attached to the transmission of such material may be borne by advertising. Accordingly, the side of the sheet recording material on which the intelligence which is transmitted is not recorded, 45 that is to say the back of the material, may be printed with advertising matter which is properly arranged with respect to each sheet of transmitted material; that is to say, for instance, if the normal size of the picture or intelligence 50 which is to be transmitted is of the order of say 11" or 12" in length, then when the sheet is cut from the roll of material on which the intelligence is recorded, the advertising matter should be in correct alignment with the recorded material. As the advertising matter would be print-

ed prior to the placing of the blank roll of recording material in the machine, naturally not only must the recording be synchronous as set forth in our application Serial Number 133,135, filed March 26, 1937, but the action of the cutting device must be definitely related to the action of the machine.

The material has in general been passed on to some form of collecting or supporting apparatus after it has been cut into sheets. The most desirable form of support has in general consisted of two cylindrical bars of nominal diameter spaced apart with regard to each other and hence comprising a divided support for the sheet. The bars have been maintained at an angle with 10 respect to each other so that at or near one portion of their length the sheet material was more narrow than the spacing of the bars, and hence would fall between the bars into a collecting pan or tray. Difficulty arose due to the fact that the 15 paper had a tendency to become electrostatically charged during its passage through the machine and across the bars, and as a result tending to freeze against the bars or curl, and our stacking mechanism has been so arranged that this problem is overcome.

It is also within the contemplation of those skilled in this particular art that the average user of this machine may very easily forget and leave the machine running for a time which under certain circumstances might be undesirable. Therefore, we provide in conjunction with the stacking mechanism a means which will automatically shut off the machine when the amount of material which has been piled in the stacking 30 tray has reached a predetermined value.

It is also an object of our invention to provide a stacking mechanism which will neatly and effectively stack the sheets of recorded material, and it is a still further object of our invention 40 to provide a device which will automatically render the machine inoperative when the amount of material collected in the collecting tray has reached a predetermined value.

The invention will best be understood by reference to the drawing in which

Fig. 1 shows one embodiment of the invention.

Referring to Fig. 1, there is shown the details of one form of cutting apparatus and the stacking apparatus and their relative arrangement with 50 respect to the rest of the machine. It should be borne in mind that the drawing is not to scale but is drawn purely for the purpose of showing the inventive concept and correlation of parts. The facsimile receiver frame 10 is 55

skeleton-like in nature and a portion of the supporting framework is indicated by this numeral. Supported by the frame is a driving motor (not shown for purposes of clarity) which is adapted to drive the various rotating parts of the apparatus. The recording drum 11 is driven by the driving motor, and supported in intimate relationship thereto are the presser or striker bars 12. The recording material 13 is passed across the periphery of roller 14 to the periphery of drum 11, and thence over friction drive rollers 15 to the friction drive rollers 16, thence past the cutting mechanism to friction rollers 17. The carbon material has not been shown since it is fed merely by means of drive rollers from the roll, thence into intimate relationship with the recording paper at the recording drum and then is re-rolled, and this apparatus as claimed does not concern either the movement of nor the disposal of the carbon paper. The driving motor drives a shaft 20 which is appropriately mounted in bearing members and contains at various portions 21 and 22 worm arrangements which are adapted to drive or cause to rotate friction roller 16 and the shaft 23 with the correct relative speeds each to the other. Mounted on shaft 23 are two cam members 24 and 125 with appropriate slots cut into their periphery.

The action of the stacking device is as follows: It will have been noted that the slot cut in the periphery of cam 125 is in advance of the position of the slot cut in the periphery of the cam 24. The reason for this is that the recording material must travel a fair distance after it has been cut before it may be stacked and, of course, this timing may be made by the positioning of the controlling slots in the two cams referred to. When the cam 125 rotates to such a position that the cam rider 100 gets to the edge of the slot contained therein, upon a small turning of the cam, the arm 20 will plunge into the slot due to the action of spring 28. When this is done the arm 102 is drawn out of supporting relationship with respect to detent 106 and withdraws a considerable distance therefrom. When this withdrawal takes place, the unit consisting of arms 107, 109, 110, and 111 will, due to gravity, rotate about axis 108, thus giving the paper a short push downwardly through the bars 112 and into the stacker tray. The position of this member comprising elements 110 and 111 when it drops is shown in dotted form. The downward motion is however limited since the backward motion of the crank arm 101 is not comparatively great and, therefore, the detent pin 106 will come sharply into contact with the arm 102. Since this arm is held by a spring 104, it will act as a resilient buffer, and also as the rider 100 moves upwardly out of the slot in the cam 125, the detent 60 will be pushed upwardly again in a comparatively short time, thus rotating arm 107 about the axis 108 and withdrawing the bars 111 from contact with the paper.

It has been hereinbefore stated that one of the objects of this invention was to provide a device which, when the recording material had been stacked to a predetermined height, the machine would automatically shut off so as to obviate continuous running of the machine when the material is not removed. For this purpose, there is provided on the same shaft as is the member 107, an elliptically shaped cam 82 and, adjacent thereto are two electrical contacts 81. Also on the shaft on which is mounted the two cams 24 and 75 125 is mounted a third cam 82 having a rela-

tively small slot cut in its face, and appurtenant thereto is a rider and arm 83, the latter being so mounted that it will not drop into the cam slot when the slot comes opposite it but will merely engage with the face of the cam as the face rotates opposite it. 5

The action of this arrangement is as follows: Normally, the slot in cam 82 will come opposite the contactor 83, which incidentally forms an electrical switch with the cam at a time when the dropper, whose arm is indicated at 109, is being actuated. The contacts closed by the elliptical cam form a switch which is joined in parallel to the switch arrangement formed by the cam 82 and the rider and arm 83. Now, as a result, during normal operation of the machine the contacts 81 remain open, and at the time when the slot in 82 comes opposite the rider, the electric motor energizing circuit would be broken but for the fact that its parallel switch arrangement which comprise the contacts 81 are forced upwardly into contact with each other by the elongated edge of the elliptical cam forcing against the contacts. These contacts close when the dropper is almost completing its upward swing and, in actual practice, the slot in the cam 82 comes opposite the rider on arm 83 at a time when the dropper is at the bottom of its stroke. Now, where the material is normally removed from the tray, the downward swing of the dropper is sufficiently great to close the contacts 81. However, as the material piles up in the tray, the downward swing of the dropper is limited and, accordingly, one of the contacts 81 is not forced upwardly by the elliptical cam quite enough to 30 join with the other contact, and as the slot in cam 82 comes opposite the contact on arm 83, this switch is also broken and the motor circuit is de-energized, whereas normally with the arm taking its full drop, one of these two switches is closed 35 at all times and it is only when both remain open that the motor stops. This will, of course, depend on the downward swing of the dropper and is entirely predetermined and, therefore, can be set for any desired amount of paper stacked in 40 the stacking tray. 45

What is claimed is:

1. A sheet material stacking device comprising an apertured support over which said sheet material is adapted to be passed, a pivoted first lever arm, means for subjecting said lever arm to a stress tending to turn said arm about its pivot, means for normally opposing said stress, said latter means being adapted to intermittently release said opposing stress in synchronism with the passage of said material, a second pivoted lever arm, a detent mounted on said second arm, an arm joined to said second arm and adapted to force the sheet material through the apertured support, and a member joined to said first lever arm, and a resilient member connected to said latter member and to said first lever arm whereby said latter member acts as a resilient support to said detent. 55

2. A sheet material stacking device comprising an apertured support means for said sheets, a slotted cam, a pivoted first lever arm, a cam rider joined to said first arm and adapted to follow the peripheral contour of said cam, spring means joined to said lever arm and adapted to keep the 70 cam rider into forced relationship with said cam face, a second lever arm, means operable by said second lever arm to force said sheet material through the aperture in said material support, and independent means joined to each of said 75

lever arms for resiliently supporting the second of said lever arms by the first of said lever arms in one direction of its motion, said independent means comprising a detent device operatively associated with one of said lever arms and means operatively associated with the other of said lever arms and in contact with said detent, said latter means being fixedly held against forces applied thereto from one direction and resilient to forces applied thereto from the opposite direction.

3. Apparatus in accordance with claim 1, wherein said apertured support comprises a plurality of rodlike members spaced apart from each other.

15 4. A sheet material stacking device comprising an apertured support over which said sheet material is adapted to be passed, a pivoted first bell crank lever, means pivotally fixed to said first bell crank lever and adapted to contact said sheet material when said bell crank lever is moved about the pivot thereof, a detent mounted on one arm of said bell crank lever, a cam member having a portion of the periphery thereof irregular in contour, a second bell crank lever pivotally supported, a detent device mounted on one of the arms of said second bell crank lever, means for normally forcing the detent device mounted on

said second bell crank lever into engagement with the peripheral face of said cam member whereby said bell crank arm is moved about the pivot thereof in accordance with the contour of the peripheral face of said cam member and independent means mounted on said second bell crank lever and resiliently held against the detent member mounted on said first bell crank lever, for normally holding the member pivotally mounted on said first bell crank lever and adapted to contact the sheet material out of engagement with said sheet material and for withdrawing the support therefrom in accordance with changes in the peripheral contour of said cam member.

10 5. Apparatus in accordance with claim 4, wherein said independent means comprises a lever arm pivotally supported between extremities thereof by said second bell crank lever and having a detent device mounted adjacent one end thereof and a spring member for forcing said detent normally into engagement with an edge of said second bell crank lever.
